Attorneys

UNITED STATES PATENT OFFICE.

MAX HARRIS, OF PHILADELPHIA, PENNSYLVANIA, ASSIGNOR OF ONE-HALF
TO WILLIAM J. EIFELD, OF SAME PLACE.

DESIGN FOR A PUZZLE-BOARD.

SPECIFICATION forming part of Design No. 29,249, dated August 16, 1898.

Application filed July 20, 1898. Serial No. 686,468. Term of patent 7 years.

To all whom it may concern:

Be it known that I, MAX HARRIS, a citizen of the United States, residing in the city and county of Philadelphia, State of Pennsylvania, have invented and produced a new and original Design for a Puzzle-Board, of which the following is a specification, reference being had to the accompanying drawings, forming part thereof.

10 The leading feature of my design for a puzzle-board is a field and a laterally-opening pocket on said field, said pocket simulating a bottle lying on its side.

Figure 1 represents a plan view of a puzzle-board embodying my design. Fig. 2 represents a vertical section thereof on line $x x$, Fig. 1.

In the drawings, A designates a field from which rise the fence B and interior walls C,

the latter having throats D therein, the passages E between said fence and walls being in communication with each other and the center of the field at said throats.

F designates a pocket simulating a portion of a bottle laid on its side on the field, at or about the center thereof, the mouth of the bottle being a lateral opening or inlet for the pocket.

Having thus described my invention, what I claim as new, and desire to secure by Letters Patent, is—

The design for a puzzle-board substantially as shown and described.

MAX HARRIS.
